UNITED STATES PATENT OFFICE.

JOHN THOMAS NAGLE, OF BUTTE, MONTANA.

FUSE-IGNITER.

SPECIFICATION forming part of Letters Patent No. 660,220, dated October 23, 1900.

Application filed June 7, 1899. Serial No. 719,671. (No model.)

To all whom it may concern:

Be it known that I, JOHN THOMAS NAGLE, a citizen of the United States, residing at Butte, (post-office address,) in the county of 5 Silver Bow and State of Montana, have invented certain new and useful Improvements in Igniting Devices for Fuses; and I do hereby declare that the following is a full, clear, and exact description of the same, reference 10 being had to the annexed drawings, making a part of this specification, and to the letters of reference marked thereon.

The object of the present invention is to provide a simple, safe, and comparatively 15 inexpensive igniting device that may be conveniently attached to fuses for igniting same without the use of giant-powder and flame in the hands of the operator preparatory to setting off a blast or explosion; and the invention 20 consists in a device of the above character, substantially as shown in the drawings and hereinafter described and claimed.

Figure 1 of the drawings is a perspective view of a fuse-igniter constructed in accordance with my invention and showing the end 25 of the fuse connected thereto; Fig. 2, a longitudinal section of the device with the fuse removed.

In the accompanying drawings, A represents a tube of copper or other metal or of 30 any suitable material found best adapted to the purpose, which tube may be of any desirable length and of a diameter to properly fit over the end of the fuse, as shown in Fig. 35 1 of the drawings. One end of the tube A has a filling C of any suitable combustible composition, but preferably of a composition consisting of the following ingredients: sulfur, one part; sugar, one part; bichromate 40 45 potash, one part; oxid manganese, one part; chlorate potash, sixteen parts; litharge, six parts; charcoal willow, four parts; acacia, four parts. The tube A is supplied with this composition a portion of its length, leaving a space back of it for the reception of the end

of the fuse, as indicated at B in Fig. 1 of the drawings. The composite combustible filling C extends beyond the end of the tube, so that a portion will be exposed for convenience in igniting it by means of a friction-match 50 tip D, which is embedded in the composition and projects a sufficient distance from the same, so that it may be conveniently ignited by friction. The tip D may be composed of any of the well-known friction-match com- 55 pounds as found most preferable.

The exposed portion of the filling C or that which extends beyond the end of the tube A forms a composite head and not being confined within the tube renders the ignition 60 thereof more certain when the match-tip is ignited.

The exposed portion of the filling C and the match-tip D are rendered impervious to moisture by a coating E of paraffin or other suitable waterproof substance.

This device to which the fuse is connected is both simple and comparatively inexpensive, and the ignition of the fuse is certain and reliable without danger or risk to the 70 operator from premature explosion.

Having now fully described my invention, what I claim as new, and desire to secure by Letters Patent, is—

An igniting device for fuses, consisting of 75 a suitable tube, a composite combustible filling therein extending beyond one end of the tube to form an exposed portion, a friction-match tip embedded in the composite filling, and a waterproof coating covering the exposed portions of the filling and the match-tip, substantially as and for the purpose set forth.

In testimony that I claim the foregoing as my own I have hereto affixed my signature in 80 the presence of two witnesses.

JOHN THOMAS NAGLE.

Witnesses:

EDWARD W. HARNEY,
W. M. BICKFORD.
